FOREIGN PATENT DOCUMENTS

GB 1209255 10/1970

Primary Examiner — Katrina A Betton(74) *Attorney, Agent, or Firm* — Barnes & Thornburg LLP(57) **CLAIM**

We claim the ornamental design for a cargo restraint device, as shown and described.

DESCRIPTION

FIG. 1 is an upper perspective view of a cargo restraint device in accordance with our new design;

FIG. 2 is a left-side elevation view of the cargo restraint device of FIG. 1;

FIG. 3 is a right-side elevation view of the cargo restraint device of FIG. 1;

FIG. 4 is a rear elevation view of the cargo restraint device of FIG. 1;

FIG. 5 is a front elevation view of the cargo restraint device of FIG. 1;

FIG. 6 is a top plan view of the cargo restraint device of FIG. 1; and,

FIG. 7 is a bottom plan view of the cargo restraint device of FIG. 1.

The broken lines depict portions of the cargo restraint device that form no part of the claimed design.
